UNITED STATES PATENT OFFICE

98,811

DESIGN FOR A WOVEN FABRIC

James D. McDowall, Oak Park, Ill.

Application January 2, 1936, Serial No. 60,372

Term of patent 7 years

To all whom it may concern:

Be it known that I, James D. McDowall, a citizen of the United States, residing at Oak Park, in the county of Cook and State of Illinois, have invented a new, original, and ornamental Design for a Woven Fabric, of which the following is a specification, reference being had to the accompanying drawing, forming part thereof.

In the accompanying drawing, the figure shows a portion of fabric with its included design.

I claim:

The ornamental design for a woven fabric, as shown.

JAMES D. McDOWALL.
